COMBINED PORTABLE CRIB AND COMPARTMENTED STORAGE CONTAINER

Percy E. Grooms, 12381 Fenton Road,
Fenton, Mich. 48430

Filed Feb 27, 1968, Ser. No. 10,742

Term of patent 14 years

Int. Cl. D6—01

U.S. Cl. D5—5

FIG-1

FIG-2

FIG-3

FIG-4

FIG-7

FIG-6

FIG-8

FIG-9

FIG-10

FIG-11

FIG. 1 is a perspective view of a combined portable crib and compartmented storage container, showing my new design;

FIG. 2 is a top plan view;

FIG. 3 is a side elevational view, the opposite side being the same in appearance except that the opening on the side is not present;

FIG. 4 is an end elevational view; the opposite end being the same in appearance;

FIG. 5 is an exploded perspective view;

FIG. 6 is an end view of the crib portion;

FIG. 7 is a top plan view thereof;

FIG. 8 is a side elevational view thereof;

FIG. 9 is a top plan view of the partition insert;

FIG. 10 is a side elevational view thereof; and

FIG. 11 is an end elevational view thereof.

I claim:

The ornamental design for a combined portable crib and compartmented storage container, substantially as shown and described.
